UNITED STATES PATENT OFFICE.

WILLIAM H. McMULLEN, OF WHITESTONE, NEW YORK.

STEERING OR STABILIZING DEVICE FOR AEROPLANES.

1,237,072.

Specification of Letters Patent. Patented Aug. 14, 1917.

Application filed January 6, 1917. Serial No. 140,976.

To all whom it may concern:

Be it known that I, WILLIAM H. McMULLEN, a citizen of the United States, residing at Whitestone, in the county of 5 Queens and State of New York, have invented new and useful Improvements in Steering or Stabilizing Devices for Aeroplanes, of which the following is a specification.

- 10 This invention relates to a steering or stabilizing device for aeroplanes, such as rudders and ailerons or other balancing elements, the primary object of the invention being to provide a steering or stabilizing 15 plane which is adapted to be adjusted through the medium of control cables in such a manner as to avoid stretching or slackening of the cables in the controlling movements of the planes.
- 20 A further object of the invention is to provide a steering or stabilizing plane which, when adjusted for a positive controlling action, will operate with a minimum of head resistance, thus overcoming the objection of 25 this character commonly present in the operation of steering and stabilizing planes in common use.

A still further object of the invention is to provide a steering or stabilizing plane 30 which diminishes side drift or skidding and at the same time is not liable to bind or to be otherwise constricted in its movements, and which, by reason of its construction, is more effectually braced and guided in its 35 movements than steering and controlling planes of ordinary construction.

With these and other objects in view, the invention consists of the features of construction, combination and arrangement of 40 parts hereinafter fully described and claimed, reference being had to the accompanying drawing in which:—

Figure 1 is a rear perspective view of a portion of an aerofoil or supporting plane of 45 an aeroplane, showing the application of the invention in the form of an aileron.

Fig. 2 is a top plan view of the same.

Fig. 3 is a fore-and-aft section through the plane taken on the line 3—3 of Fig. 2.

50 While, for purposes of exemplification, the invention is herein shown in the form of an aileron, it is to be understood that the principles of the invention may be embodied in a vertical or horizontal rudder or any other 55 suitable type of steering or stabilizing plane.

Referring to the drawing, 1 designates an

aerofoil or supporting plane of an aeroplane, which is shown as provided with a cut-out corner space or recess 2 to receive an aileron or balancing plane 3. This aileron or balancing plane is coextensive in size with the recess and is normally arranged in the plane of the main plane 1, so as to form a part of the supporting surface thereof, and is adjustable vertically above and below the 60 plane of the main plane 1 for stabilizing and controlling actions.

The aileron 3 is hinged at its forward edge to the main plane 1, as indicated at 4, for adjusting movements as set forth, and 70 carries a vertically disposed fin or vane 5. This fin or vane comprises a substantially triangular body portion, having its forward end 6 curved on the arc of a circle. The triangular body portion proper of the vane is 75 bifurcated longitudinally in the line of its axis to form a slot 7 receiving the plane 3 which extends therethrough, the vane 5 being extended transversely of said plane 3 and having its divided portions arranged 80 to form upper and lower counterpart stability fins.

The plane 3 and vane 5 may be constructed of any suitable material and rigidly united in any suitable manner, and the curved or 85 rounded enlarged portion of said vane is designed to perform the function of a crank element to which the controlling cables are coupled, and whereby the plane 3 may be adjusted. As shown, the rear portion of 90 the main plane 1 is formed with a transverse slot 8 which receives the rounded or partially circular portion of the vane 5, which extends in advance of the forward hinged edge of the aileron 3, the vane 5 95 thus serving further as a bracing or strengthening element for the aileron and as a guiding member movable between the walls of the slot 8, whereby any deflection of the moving parts from a true vertical movement 100 is prevented and any tendency of the parts to bind when in operation effectually avoided. Thus it will be seen that the vane 5 strengthens the aileron to adapt it to more 105 effectually withstand the strains imposed thereon and also guides said aileron in its movements so as to avoid any liability of undue play and wear and tear upon the hinges 4.

The rounded surfaces of the portion 6 of 110 the vane 5 form in effect quadrants, and these quadrants are grooved, as shown at

9, to receive the outer ends of controlling cables 10 and 11, which are fixed at their extremities thereto, as indicated at 12, said cables passing over guide pulleys 13 to the 5 body of the machine for connection with a suitable control device in the usual manner. Preferably the main plane 1 is made hollow and the cables are extended along the interior thereof, thus concealing and protecting 10 them, with the result of reducing liability of the cables becoming entangled and their movements interfered with or of said cables being exposed and acting as resistance surfaces.

15 The guide pulley 13 in proximity to the inner end of the slot 8 forms a guide for the ends of the cables fastened to the quadrant surfaces of the vane 5, and properly disposes the respective cables for reverse 20 movements in unison for up-pulling and down-pulling actions to correspondingly adjust the aileron 3. It will thus be understood that when the cable attached to the upper quadrant surface is drawn upon and 25 the cable attached to the lower quadrant surface relaxed the plane 3 will be adjusted upwardly, while reverse movements of the cable ends will result in the plane 3 being moved downwardly, whereby said plane may 30 be easily and conveniently operated for controlling actions. It will be observed that in all of the adjustments of the ends of the cables attached to the curved or quadrant surfaces of the vane, said cables will lie in 35 contact with said surfaces, which will always maintain the same taut, whereby the cables will be prevented from stretching or becoming loose and tangling and catching in any possible obstructions, or in being 40 exposed to offer a head resistance to the flight of the craft. It will be understood, of course, that the vane 5, in addition to its functions hereinbefore set forth, serves as a vertical stability surface to prevent side 45 drift or skidding of the machine, whereby such objection is prevented.

I claim:—

1. A controlling device for air craft comprising an adjustable lateral balancing 50 plane, a vane carried by said plane between the ends of the latter and disposed at an angle thereto, and means connected with the forward end of the vane for effecting adjustments of the plane.
2. A controlling device for air craft comprising an adjustable plane, a vane carried 55 by the plane and disposed in a plane per-

pendicular thereto, said vane being provided with surfaces forming arcs of circles, and controlling cables secured to said surfaces and movable in opposite directions to effect adjustments of the plane. 60

3. A controlling device for air craft, comprising a plane, a vane carried by and disposed at an angle to the plane, and projecting 65 above and below the same to form anti-skidding surfaces, said vane extending beyond the leading edge of the plane and means connected with the forward end of said vane for controlling the plane. 70

4. In a controlling device for air craft, the combination of a main plane having a slot therein, a small plane hingedly connected with the main plane for adjusting movements, a vane carried by the small plane and 75 disposed at an angle thereto and having a portion projecting into said slot and movable therein, and means connected with said projecting portion of the vane for adjusting said small plane. 80

5. In a controlling device for air craft, the combination of a main plane having a slot therein, a small plane hinged to the main plane for adjusting movements, a vane carried by the small plane and projecting at 85 right angles above and below the same, said vane comprising a substantially triangular body portion having its enlarged end projecting beyond said small plane and into said slot in the main plane and provided 90 with curved surfaces forming quadrantal portions, and cables connected with said quadrantal portions of the vane for communicating adjusting movements to the small plane. 95

6. In a controlling device for air craft, the combination of a hollow main plane having a transverse slot extending through one of its edges, a small plane hinged to said edge of the main plane for adjusting movements, a vane disposed at an angle upon the small plane and having a portion projecting therefrom into said slot, said projecting portion of the vane being formed 105 with quadrantal surfaces above and below its center, guiding elements on the main plane, and cables guided by said elements and extending through the hollow main plane and having terminal portions secured to said quadrantal surfaces for communicating motion through the vane to the small plane. 110

In testimony whereof I affix my signature.
WILLIAM H. McMULLEN.
